UNITED STATES PATENT OFFICE.

FREDERICK E. STANLEY, OF WATERBURY, CONNECTICUT, ASSIGNOR TO SCOVILL MANUFACTURING COMPANY, OF WATERBURY, CONNECTICUT, A CORPORATION OF CONNECTICUT.

TACK-FASTENED BUTTON.

1,142,376.

Specification of Letters Patent.

Patented June 8, 1915.

Application filed April 28, 1913. Serial No. 764,223.

To all whom it may concern:

Be it known that I, FREDERICK E. STANLEY, a citizen of the United States, residing at Waterbury, in the county of New Haven

5 and State of Connecticut, have invented a certain new and useful Improvement in Tack-Fastened Buttons, of which the following is a full, clear, and exact description.

Buttons designed to be secured to a garment by means of tacks forced through the garment from one side thereof into the buttons on the other side, with such pressure as to upset the points of the tacks within the buttons and thus firmly attach them to 10 the garment, are well-known; and it is equally well-known that such buttons have contained within them some sort of anvil for receiving the thrust of the tack and upsetting its end, and anchoring it therein.

15 Sometimes a filler piece has been added to take up or compensate for extra depth in the interior of the button. Also these interior elements have served as reinforces, and as means to fill up the space in the button along 20 the length of the tack. But I am unaware of any instance prior to my invention herein disclosed, where a single structure has served

25 all of these purposes, and in addition has been of such character as to resist lateral strains in setting or attaching the buttons and in use. Where the anvil or filler is loose within a metal button, the resulting rattling is objectionable. Unless the interior construction affords a support for the 30 face or cap of the button, such face or cap is apt to spring when the button is set, thus giving the loose piece greater room for undesirable and noisy movement. Obviously, the button face or cap cannot be adequately 35 protected from disfigurement under such circumstances. When the face or cap is 40 ornamented or, as is equally common, has the user's name or trademark embossed in it, there is still more urgent need of a stable 45 interior construction. If the interior construction be in two or more parts, the cost of manufacture of the buttons is correspondingly increased. By my invention these 50 objections are met and overcome, and I am enabled to produce a button of relatively

less weight, having fewer parts to handle in assembling, and costing less to make and sell, and also to use thinner and less expensive stock for the cap or face.

The invention consists in a combined anvil 55 and filler, for tack-fastened buttons, made of a single piece drawn to shape, and having a flat head portion which serves the three-fold purpose of an anvil, a filler and a button-cap reinforce, said combined anvil and 60 filler also having its tack point receiving and anchoring portion made as a tapering extension from the flat head, so as, first, to guide the tack point into the combined anvil and filler; second, to support said tack and 65 button while being set and while in use against deformation and release under strains, and, third, to afford an unbroken whole-walled chamber in which the tack point is upset and held to fasten the button 70 to a garment, this unbroken whole-walled characteristic of the chamber formed in and by the tapering extension serving to resist the strains incident to setting the button and to prevent the deformation or spreading of 75 the device in use, as I will proceed now to explain and finally claim.

In the accompanying drawings illustrating the invention, in the several figures of which like parts are similarly designated, 80 Figure 1 is a plan view, and Fig. 2 is an edge view of a discous blank from which the device of the invention may be produced by a succession of operations. Fig. 3 is a longitudinal section of the cupped blank. 85 Fig. 4 is a longitudinal section of the cupped blank with the head and shank in embryo. Fig. 5 is a longitudinal section showing the next operation. Fig. 6 is a longitudinal section showing the final operation and completed device. Fig. 7 is an elevation of the 90 finished device. Fig. 8 is a longitudinal section of one form of button containing the device of this invention. Fig. 9 is a longitudinal section showing a button like that of Fig. 8 set or tacked upon a piece of cloth, 95 and illustrating the relation of the upset or clenched tack to the button and its parts.

The interior piece of this invention is produced by a succession of drawing and press- 100

ing operations, from a discous blank 1, Figs. 1 and 2. This blank is first drawn into cup or shell form, as shown at 2 in Fig. 3, and this cup is next treated so as to form an embryotic head 3 and shank 4, Fig. 4. Next the blank is subjected to the action of suitable dies by which the head is flattened out transversely, as at 5, and the shank drawn up close against the head, as shown in Fig. 10 5, and then the incipient head is straightened out as at 6, Figs. 6 and 7, and the shank closed in so as to provide the tack point receiving cavity 7 of frusto-conical section and the relatively short tack point 15 guiding and staying tubular portion 8 of substantially cylindrical section. This device, so produced, is suitable for use in various kinds of buttons, but is specially designed for use in metal buttons composed of 20 a back 9 having a relatively long hub, 10, and made of relatively hard metal, and a face or cap 11 of relatively thin metal, such as brass, and adapted to receive any suitable design, advertisement, trademark, or other marks, the back and face being united by closing the latter upon the former. Within the chamber formed by the back and face is arranged the combined anvil and filler of 25 this invention, so that its head is located between the back and face and in contact with 30 both, so as to afford an adequate support for the face and to prevent rattling and springing, and its shank extending down into the hub to receive and guide the tack point and hold it and the button in alinement and take 35 the lateral strains imposed in setting the button and in use.

As shown in Fig. 9, the button is attached 40 to a garment, represented at 12, by locating it on one side and then driving the tack 13 from the opposite side, through the garment and into the button. The hub of the button has the tack-hole 14, through which the tack point enters and thence passes into the 45 shank of the device, up into the tack receiving cavity 7 where it meets the flattened head, and is upset or clenched, as indicated at 15, and so deformed as to fill the cavity sufficiently to fixedly unite the button and 50 tack.

Since the wall of the shank of the device is whole, or solid or unbroken, it is apparent that all strains on the tack or button in any direction will be successfully and effectively 55 met by said shank, and all danger of the shank disrupting or spreading is avoided.

The contour of the combined anvil and 60 filler may be altered to suit buttons of various shapes, so long as it embodies the tack-clenching and face or cap-supporting head and the shank integral therewith and forming the clenching cavity and tack point guide and support.

By my construction, comparatively thin and inexpensive metal may be used for the 65 cap or face, since it is fully supported by the combined device and protected against rupture or deformation.

It is to be noted that not only is the combined anvil and filler of the present invention distinguished over the prior art by its being drawn to shape, but it is further distinguished by being supported wholly within the button-head, its own laterally extended head resting upon the back, as already 70 stated, and its tubular mouth terminating within the hub, so that it does not come into contact with the article to which the button is attached and consequently is relieved of setting pressure that might tend to spread 75 or deform it. Further, this combined anvil and filler is in no wise dependent upon the hub either for its support or its connection with the button. In my construction the hub and not the combined filler and anvil 80 fixes the relation of the button to the garment and the combined filler and anvil performs its designated functions of receiving, 85 clenching and anchoring the tack and supporting the button face regardless of its relation to the garment or other article to 90 which the button is applied.

What I claim is:—

1. A combined anvil and filler for a tack-fastened button, for clenching and anchoring the tack used to secure the button to an article, same consisting of a unitary structure drawn to shape and having a flat head portion and a whole-walled tapering hollow extension beyond which the flat head portion extends laterally all around, the tapering portion having a substantially tubular unbroken cylindrical end portion through which the tack point is introduced into the interior of the hollow extension to be 105 clenched therein, the flat head only of the hollow extension receiving the impact of the tack in the act of setting and the unbroken cylindrical end portion resisting the longitudinal strain and overcoming the tendency 110 to spread.

2. A tack-fastened button, having a tack clenching and anchoring member for securing the button to an article, said member made of a single piece cup drawn to shape 115 and including a flat head portion and a whole-walled tapering hollow extension beyond which the flat head portion extends laterally all around, the tapering portion having a substantially tubular unbroken cylindrical end portion through which the tack point is introduced into the interior of the hollow extension and therein clenched, combined with a hubbed back and a face closed 120 down over the back, the said tack clenching 125 and anchoring member located between the

back and face and resting upon the back and opposed by the face, its hollow extension entering the hub and its terminal portion inclosed by said hub and out of contact with
5 the article to which the button is applied, and also out of supporting contact with the hub.

In testimony whereof I have hereunto set my hand this 26 day of April A. D. 1913.

FREDERICK E. STANLEY.
